UNITED STATES PATENT OFFICE.

CHARLES EDWARD MURRAY, JR., OF TRENTON, NEW JERSEY.

DESIGN FOR A TIRE.

Application filed September 18, 1922. Serial No. 3,757. Term of patent 14 years.

To all whom it may concern:

Be it known that I, CHARLES EDWARD MURRAY, Jr., a citizen of the United States, residing at Trenton, in the county of Mercer and State of New Jersey, have invented a new, original, and ornamental Design for Tires, of which the following is a specification, reference being had to the accompanying drawing, forming part thereof.

Figure 1 is a plan view of a section of the tire illustrating my new design; and
Figure 2 is a vertical cross-sectional view thereof.

What I claim is:—
The ornamental design for a tire as shown.

CHARLES EDWARD MURRAY, Jr.
